UNITED STATES PATENT OFFICE.

PIETER KUYKEN, OF ZAANDAM, NETHERLANDS.

DOUBLE-ACTING TWO-STROKE INTERNAL-COMBUSTION ENGINE.

Application filed August 22, 1924, Serial No. 733,624, and in the Netherlands January 31, 1924.

My invention relates to double-acting two-stroke internal combustion engines having scavenging air ports in the middle region of the cylinder wall.

5 In order that the cylinder of a two-stroke internal combustion engine may be efficiently scavenged through an air port or ports disposed opposite the outlet it is essential that the air should flow, as nearly as 10 possible, in the direction of the axis of the cylinder to expel the combustion gases from the combustion space.

In a double-acting engine the scavenging air should be directed alternately towards 15 the one and the other end of the cylinder. This desideratum may be realized with the employment of two series of ports having their axes suitably inclined towards the corresponding cylinder ends, but this construction requires an appreciable extension of the cylinder and involves the employment of a comparatively long and heavy piston. Also the arrangement of a rotary valve controlling a single series of scavenging air ports 20 of greater axial length than the exhaust ports is open to like criticism.

My invention has for its object to provide an improved arrangement for effective scavenging of the cylinder with only one scavenging port or series of ports. With this object in view I provide a guide member movable laterally and more or less parallel to the axis of the cylinder and cooperating with the scavenging ports, said guide member being formed and actuated in such a manner as to direct the flow of scavenging air alternately to the one and to the other end of the cylinder. Preferably the said guide-member conforms to the interior of 35 that portion of the air inlet chamber which is adjacent to the cylinder lining and the walls of which are inclined to the axis of the cylinder, the length of said guide-member in the direction of the axis of the cylinder being less than that of the chamber, so 40 that between the guide member and the inclined chamber walls inclined slots or passages are formed, through which in alternation, dependent upon the position of the guide member in the chamber, the air is caused to flow in the required direction into the cylinder as soon as the piston unmasks the scavenging port or ports. Between the guide member and the chamber 45 walls may be inserted suitable packing, for instance partly loose leather strips, for clos-

ing the narrow passage that may be left at that side of the guide member at which the scavenging air is not to be discharged.

Instead of a guide member in the form of a block or displacer co-operating with the walls of the air inlet chamber to constitute nozzles for forming the air jets, a slide valve, the ports of which act as nozzles, may be used. The use of a slide valve, however, 65 has the drawback that a slide face is difficult to be trued at this place and that it requires a comparatively spacious air chamber, whereby the water-cooled portion of the cylinder is reduced. A rotary valve 70 cannot be used in arrangements according to the invention.

In short I prefer to employ a simple guide member to obtain the objects of my invention. Suitable actuating mechanism 75 for such member comprises two pairs of crank arms of equal length secured to parallel shafts, one of said shafts being oscillated in timed relation with the reciprocation of the piston. The length of stroke of 80 the guide member should be such that said member does not contact with the air chamber walls, whereby a noiseless operation is obtained and seizing is avoided.

The annexed drawing illustrates diagrammatically, and by way of example only, one embodiment of my invention.

Fig. 1 is a part elevation and part axial section of the cylinder and adjacent parts of a double-acting two-stroke internal combustion engine,

Fig. 2 is a view similar to Fig. 1, with the moving parts in different positions, and

Fig. 3 is a sectional view on line III-III of Fig. 1.

Movable in the cylinder 1 is a piston 2 shown in its lowermost position in Fig. 1, and in its uppermost position in Fig. 2. The scavenging air is admitted into the cylinder through ports 3 and the combustion gases are expelled through ports 4. The top and bottom walls of the chamber 5 forming the end of the scavenging air conduit are conical. Said chamber accommodates an arcuate movable member 6, that side of the member 6 adjacent to the cylinder presenting two correspondingly shaped conical surfaces. When the member 6 assumes its uppermost position (Fig. 1) it leaves a conical passage 7 directing the flow of air upwards, and when said member has moved into its other extreme position (Fig.

2) there is left a conical passage 8 which directs the air to the bottom of the cylinder.

The member 6 is pivoted to two pairs of crank arms 9, 10 of equal length keyed to parallel shafts 11, 12. The shaft 11 receives oscillatory movement from a cam or eccentric 13 on the usual cam shaft 14 so that the member 6 assumes its uppermost position when the downwardly moving piston 10 uncovers the scavenging ports 3, and its lowermost position when said ports are unmasked during the return stroke of the piston.

The member 6 may be of light sheet iron 15 and may be counterbalanced by a weight or a spring so that its actuation does not consume an appreciable amount of power.

What I claim is:—

1. Scavenging means for double-acting two-stroke internal combustion engines, comprising, an engine cylinder, at least one scavenging air port in substantially the middle of the cylinder, a laterally movable member surrounding part of the cylinder 25 adjacent the scavenging air port, the member having guiding means for scavenging air inclined to the cylinder axis toward both ends of the cylinder and positioned for communicating alternatively with the air port.

2. Scavenging means for double-acting two-stroke internal combustion engines, comprising, an engine cylinder, at least one scavenging air port in substantially the middle of the cylinder, an external laterally 30 movable member embracing part of the cylinder adjacent the scavenging air port, the member having guiding means for scavenging air inclined to the cylinder axis toward both ends of the cylinder and positioned for communicating alternatively with the air port.

3. Scavenging means for double-acting two-stroke internal combustion engines, comprising, an engine cylinder, at least one scavenging air port in substantially the middle of the cylinder, a laterally movable member surrounding part of the cylinder adjacent the scavenging air port, the member having guiding means for scavenging air inclined to the cylinder axis toward both ends of the cylinder and positioned for communicating alternatively with the air port, an air inlet chamber for the air port having walls inclined to the cylinder axis toward both ends of the cylinder, inlet ports for the scavenging air being formed alternatively by the cooperation of the inclined guiding means of said laterally movable member, and the inclined inner surfaces of the 55 walls of the air inlet chamber.

4. Scavenging means for double-acting two-stroke internal combustion engines,

comprising, an engine cylinder, at least one scavenging air port in substantially the middle of the cylinder, an external laterally 65 movable member surrounding part of the cylinder adjacent the scavenging air port, the member having guiding means for scavenging air inclined to the cylinder axis toward both ends of the cylinder and positioned for communicating alternatively with the air port, an air inlet chamber for the air port having walls inclined to the cylinder axis toward both ends of the cylinder, inlet ports for the scavenging air being formed alternatively by the cooperation of the inclined 70 guiding means of said laterally movable member, and the inclined inner surfaces of the walls of the air inlet chamber.

5. Scavenging means for double-acting 80 two-stroke internal combustion engines, comprising, an engine cylinder, at least one scavenging air port in substantially the middle of the cylinder, a laterally movable member surrounding part of the cylinder adjacent the scavenging air port, the member having guiding means for scavenging air inclined to the cylinder axis toward both ends of the cylinder and positioned for communicating alternatively with the air port, 85 two parallel shafts, two pairs of crank arms of equal length carried by the shafts and connected to the laterally movable member, and means for oscillating one of the shafts in timed relation with the reciprocation of 90 the engine piston.

6. Scavenging means for double-acting two-stroke internal combustion engines, comprising, an engine cylinder, at least one scavenging air port in substantially the middle of the cylinder, a laterally movable member surrounding part of the cylinder adjacent the scavenging air port, the member having guiding means for scavenging air inclined to the cylinder axis toward both ends 105 of the cylinder and positioned for communicating alternatively with the air port, an air inlet chamber for the air port having walls inclined to the cylinder axis toward both ends of the cylinder, inlet ports for the scavenging air being formed alternatively by the cooperation of the inclined 110 guiding means of said laterally movable member, and the inclined inner surfaces of the walls of the air inlet chamber, two parallel 115 shafts, two pairs of crank arms of equal length carried by the shafts and connected to the laterally movable member, and means for oscillating one of the shafts in timed relation with the reciprocation of the engine 120 piston.

In testimony whereof I affix my signature.

PIETER KUYKEN.
